UNITED STATES PATENT OFFICE.

ABRAHAM A. NEWMAN, OF CHICAGO, ILLINOIS.

DESIGN FOR A CLOCK-CASE.

No. 38,377.

Specification for Design.

Patented Dec. 18, 1906.

Application filed September 19, 1906. Serial No. 335,331. Term of patent 14 years.

To all whom it may concern:

Be it known that I, ABRAHAM A. NEWMAN, a citizen of the United States, residing at Chicago, in the county of Cook and State of Illinois, have invented a new, original, and ornamental Design for Clock-Cases, of which the following is a specification, reference being had to the accompanying drawings, forming part thereof.

In the drawings, Figure 1 is a side elevation

of the clock-case, showing my new design; and Fig. 2 is a front elevation thereof.

I claim—

The ornamental design for a clock-case as shown.

ABRAHAM A. NEWMAN.
